UNITED STATES PATENT OFFICE.

JOHN H. G. ZUNNER, OF BOSTON, MASSACHUSETTS.

MEASURE-INDICATOR.

SPECIFICATION forming part of Letters Patent No. 540,130, dated May 28, 1895.

Application filed April 19, 1894. Serial No. 508,101. (No model.)

To all whom it may concern:

Be it known that I, JOHN H. G. ZUNNER, a citizen of the United States, and a resident of Boston, in the county of Suffolk and State of Massachusetts, have invented new and useful Improvements in Measure-Indicators for Pitching Apparatus, of which the following, taken in connection with the accompanying drawings, is a specification.

10 This invention relates to improvements in measure indicators for pitching apparatus for pitching barrels and although especially designed for such purpose it may to advantage be used for the purpose of measuring the flow 15 of liquids in a general way without departing from the essence of my invention.

In pitching apparatus for the purpose of coating the interior of lager beer or ale barrels with molten pitch or rosin, it is desirable 20 to employ means for regulating the quantity of liquid pitch that is to be drawn from the pitching apparatus to the barrel according to the size of the latter and for this purpose I use in connection with the stop cock or valve 25 on the discharge pipe leading from the kettle of the pitching apparatus, a measuring device actuated by said stop cock so as to indicate to the man in charge that the proper quantity of the pitch or rosin has been discharged into 30 the barrel to be pitched.

In the drawings I have represented, in Figure 1, a longitudinal section of a pitching apparatus, partly shown in elevation and having its stop-cock connected to a hydraulic 35 measuring device or quantity-indicator. Fig. 2 represents a front elevation of Fig. 1.

A, represents the furnace or fire pot of a pitching apparatus having the ash pit B below it as usual.

40 C is the kettle containing the pitch or rosin D to be heated which kettle is preferably arranged above the furnace A with an annular heating space E left between said kettle and the inclosing shell F as usual.

45 G is a discharge pipe leading from the lower part of the kettle C and provided with a suitable cock, valve, or cut off H provided with a handle h for the operator to take hold of in opening and closing said valve or cut off.

50 I represents the barrel that is to be pitched and coated on its inside with the molten pitch

or rosin from the kettle C as is common in pitching apparatus of this kind.

h' is the upwardly projecting spindle of the valve or cut off H and I have shown its upper 55 end journaled in a bearing bracket K preferably secured to the shell F and provided with a bevel gear H' having its teeth meshing in the teeth of a bevel pinion l secured to a shaft L suitably journaled in bearings in the 60 bracket K.

To the outer end of the shaft L is secured a transparent glass tube M containing liquid m and having a contracted or reduced midway orifice m' as shown in Fig. 1. The ends 65 of the tube M are graduated so as to correspond in gallons or otherwise with the flow of the liquid pitch from the discharge pipe G when the cock or valve is open. Normally the liquid m in the glass tube M is contained 70 in the lower portion thereof.

By opening the cock H the tube M is turned half a revolution causing that portion thereof which contains the liquid to be held uppermost and causing the liquid therein to pass 75 slowly through the orifice m' into the now lower compartment of said tube which is indexed or graduated to correspond in gallons, &c., with the amount of pitch passing out through the cock H and its discharge pipe G. 80 If for instance it is desired to discharge one gallon of pitch into the barrel, all that the operator has to do is to look on the tube M and when he finds that the liquid in the lower portion of said tube M reaches the mark 1 thereon 85 he knows that a gallon has been discharged into the barrel and consequently closes the cock H by which the measuring tube M is reversed and the liquid contained therein caused to run into its lower compartment 90 where it remains until its position is reversed by the next opening of the cock or valve H and so on, thus indicating to the operator the amount of pitch that has been discharged from the kettle C into the barrel I. 95

I have shown the measuring device as electrically operated by the opening of the valve or stop cock H and I have for this purpose shown an electrode h'' on the handle h adapted to be brought in metallic connection with a 100 stationary electrode g on the pipe G which electrodes are connected respectively by means

of wires h^3 and g' to the electro-magnet O as shown. H'' is a battery or current generator located in the circuit as shown. P is the register or indicator having a graduated scale 5 P' and movable index pointer p secured to the spindle p' as shown.

- I have shown a rocking armature lever Q pivoted at q and having armature q' adapted to be attracted to the electro-magnet O 10 when the circuit is closed and provided with a suitable spring r by which said armature lever is caused to vibrate as long as the circuit is closed by which its pawl shaped end Q' is caused to engage with a ratchet wheel 15 P'' on the index pointer shaft p' so as to cause the index pointer to move in front of the dial P and thus indicate the amount of liquid passing through the valve or cut off H as long as the latter is kept open.
- 20 I wish to state that I do not desire to confine myself to the exact electrical connections and mechanism as shown as any other suitable mechanism may be used without changing the essence of my invention.

- 25 Having thus fully described the nature, construction, and operation of my invention, I wish to secure by Letters Patent and claim—
1. In a measure indicator for pitching apparatus, the combination with a discharge 30 faucet directly connected to the liquid containing vessel, of a quantity indicating device comprising an oscillatory, transparent tube

having a contracted central portion forming a passage communicating with its opposite ends and bearing a fixed, determined relation 35 to the area of the discharge faucet, said tube being partially filled with a liquid and provided with a graduated scale, and means operated by the faucet for oscillating said tube, substantially as described. 40

2. In a measure indicator for pitching apparatus, the combination with a discharge faucet directly connected to the liquid containing vessel, a vertical spindle connected to the turning plug of the faucet, a bevel-gear 45 mounted upon the end of said spindle, a bevel-pinion meshing with said bevel-gear, and an oscillatory transparent tube mounted on a horizontal shaft turning with said bevel-pinion and having a contracted central portion 50 forming a passage between the opposite ends of the tube bearing a fixed, determined relation to the area of the discharge faucet, said tube being partially filled with a liquid and provided with a graduated scale, substantially 55 as and for the purpose specified.

In testimony whereof I have signed my name to this specification, in the presence of two subscribing witnesses, on this 12th day of April, A. D. 1894.

JOHN H. G. ZUNNER.

Witnesses:

ALBAN ANDRÉN,
KITTY M. HANSON.

Correction in Letters Patent No. 540,130.

It is hereby certified that in Letters Patent No. 540,130, granted May 28, 1895, upon the application of John H. G. Zunner, of Boston, Massachusetts, for an improvement in "Measure Indicators," an error appears in the printed specification requiring correction as follows, to wit: All matter between line 96, page 1, and line 24, page 2, both inclusive, should be stricken out, the same having been erroneously printed as a part of the specification; and that the said Letters Patent should be read with this correction therein that the same may conform to the record of the case in the Patent Office.

Signed, countersigned, and sealed this 2d day of July, A. D. 1895.

[SEAL.]

JNO. M. REYNOLDS,
Assistant Secretary of the Interior.

Countersigned:

JOHN S. SEYMOUR,
Commissioner of Patents.
